UNITED STATES PATENT OFFICE.

SIDNEY A. KELLER, OF NEW YORK, N. Y.

DESIGN FOR A LID FOR PUFF-BOXES OR SIMILAR ARTICLES.

SPECIFICATION forming part of Design No. 36,025, dated August 26, 1902.

Application filed July 23, 1902. Serial No. 116,746. Term of patent 3½ years.

To all whom it may concern:

Be it known that I, SIDNEY A. KELLER, a citizen of the United States, and a resident of New York, borough of Manhattan, in the county of New York and State of New York, have invented and produced a certain new, original, and ornamental Design for a Lid for Puff-Boxes or Similar Articles, of which the following is a specification.

In the accompanying drawing I have illustrated the lid or cover of a puff-box or similar article ornamented in accordance with my invention.

The leading or characteristic features of my design are the circular outline of the lid, the butterfly head, consisting of the head of a female figure having wings extending therefrom, and floral decoration partially surrounding a plain central shield.

Referring to the drawing, A represents the 20 head of a female figure having wings B B extending therefrom and below the head a plain shield C. Below the shield is the floral decoration D, the ornamentation being in relief.
